UNITED STATES PATENT OFFICE.

JOHAN G. LENHART, OF BELLINGHAM, WASHINGTON.

SUPPORTING-RACK.

1,109,430.

Specification of Letters Patent.

Patented Sept. 1, 1914.

Application filed January 3, 1912. Serial No. 669,183.

To all whom it may concern:

Be it known that I, JOHAN G. LENHART, a citizen of the United States, residing at Bellingham, in the county of Whatcom and 5 State of Washington, have invented new and useful Improvements in Supporting-Racks, of which the following is a specification.

An object of the invention is to provide a rack for supporting clothes and the like.

10 The invention embodies among other features a device for attachment to heating pipes and provided with adjustable rack members extending outwardly to support wet clothes and the like, preferably supported adjacent the heating pipe for the purpose of drying the same.

For the purpose mentioned, use is made of a band mounted to encircle a heating pipe and rigidly supported thereby and a series 20 of relatively offset flanges formed integrally with the said band and adapted to receive the inner ends of hook members, the mentioned hook members being held in supporting position by the said flanges and mounted 25 ed to swing relatively to the heating pipe.

In the accompanying drawings Figure 1 is a perspective view of the heating pipe showing my device attached thereto. Fig. 2 is an enlarged vertical sectional view taken 30 on the line 2—2 in Fig. 1. Fig. 3 is a plan view of the band, the hook members being removed therefrom.

Referring more particularly to the views, I provide a band 10 mounted to encircle a 35 heating pipe 11, the ends of the band being bent to form ears 12 provided with apertures adapted to receive a bolt 13 therethrough, on which is threadedly mounted a nut 14, the said nut being preferably provided with a squared portion 15 adapted to abut against the outer side of the band 10 to prevent any turning of the nut so that 40 when the bolt is screwed up on the nut, the band 10 will be bound to the heating pipe 11 and supported thereby.

At spaced distances portions of the band 10 are bent to form curved plates 16, 17, the plates 16 being struck outwardly and offset 45 from the upper portion of the band and the

plates 17 being struck inwardly and offset 50 from the lower portion of the band, an opening 18 being provided between each of the adjacent plates 16, 17 to receive a bent end 19 of a hook member 20, provided at its other end with an integral head 21, the free 55 end of the hook 19 being adapted to abut against the plate 17 and the portion of the hook at the point of bending being adapted to abut against the plate 16, it being readily seen by referring to the figures that the 60 plates 16, 17 are offset from the vertical plane of the band so that the opening between the plates will lie in the plane of the band. It will also be seen that when the hook members 20 are mounted as mentioned, 65 the same can be swung to various angles relatively to the band and with the provision of the device described, wet clothes can be hung adjacent the heating pipe 11 so that the heat from the pipe will quickly dry the 70 clothes.

It will be noted that the plates 16 are spaced a sufficient distance away from the plates 17 and the band 10 to permit of turning the rods from a normal horizontal position as shown in Fig. 1 into an upright position when the rods are not in use and it will be apparent that when the rods are 75 swung into an upright position as mentioned and dropped, they will be supported by the 80 head 21 engaging the outwardly struck plates 16.

The band 10 is preferably formed of an integral piece of flexible ribbon-like metal and the hook members 20 are shaped similar 85 to wire nails with the exception that the inner ends thereof are bent at approximately right angles to the body portion of the hook members.

I claim:—

90 A supporting rack for use on stove pipes or other like supports of a band encircling the support of the stove pipe with the band provided at spaced points with upper and lower semi-tubular portions struck therefrom in vertical alinement, the upper semi-tubular portions being outturned and the lower semi-tubular portions being inturned 95

to form vertical openings in the band and supporting arms carried by the band and movable therein with the inner end of each band at right angles with its body, the said 5 upper semi-tubular portions of the band being spaced from the lower semi-tubular portions of the band to permit the said right angle portion of the arm to be turned there-

in for adjusting the arms from a horizontal to an upright position. 10

In testimony whereof I affix my signature in presence of two witnesses.

JOHAN G. LENHART
